GAME AND APPARATUS

John H. Gross, New York, N. Y.

Application January 16, 1937, Serial No. 120,873

11 Claims. (Cl. 273—14)

The invention relates to a game of numbers, to a method of playing such game and to apparatus particularly designed for practicing the method.

- 5 The invention has for its primary object the providing of a variation in rolling ball games which employ numbered balls or spheres such as pool and billiards and which invention features both an element of skill in shooting a cue ball as in playing pool, and an element of chance as to which combination of numbers may be separated from a conventional pyramid arrangement of such numbered billiard balls as the result of a skillful shot.
- 10 15 The invention further contemplates the utilization of the single number on an ejected ball, or preferably the summation of two such numbers in the event of the simultaneous ejection of two such balls.
- 20 25 Referring to the apparatus aspect of the disclosure, an object of the invention is to provide a simplified form of container for billiard balls and like numbered spheres so designed and proportioned that the contained spheres can be readily mixed to assume a change in relative arrangement by shaking the container, and from which container a pair of the numbered spheres may be readily rolled out of the container on the actuation thereof in the manner prescribed by the rules of the game.

30 Various other objects and advantages of the invention will be in part obvious from a consideration of the method features of the disclosure and from an inspection of the accompanying drawing and in part will be more fully set forth in the following particular description of one method of practicing the invention, and the invention also consists in certain new and novel modifications of the preferred method and other features of construction and combinations of parts hereinafter set forth and claimed.

In the drawing:

Fig. 1 is a plan view looking down upon a pool table equipped with apparatus for playing the games herein featured and showing the container in plan and in position to be actuated;

Fig. 2 is an enlarged view in front elevation of the container shown in Fig. 1, looking at the same from the left hand side of that figure and with the closures in locked position;

Fig. 3 is a horizontal section through the container and taken on the line 3—3 of Fig. 2 looking downwardly as indicated by the arrows; and

Fig. 4 is a view partly in side elevation of the

right hand side of the container as shown in Fig. 2 and with parts broken away on the line 4—4 of Fig. 1 to show details of construction and also showing in dotted lines an elevated position of one of the closures.

In the drawing and referring first to Fig. 1 there is disclosed a flat support 10 and in the instant case shown to be the top of a pool table or other surface on which pool balls roll easily. There is positioned on the table a container 11, 10 a cue ball 12 and an actuating cue 13.

The container 11 comprises a bottom 14, triangular shaped in plan, having an apex 15 and a base edge 16 forming the side opposite the apex 15. The ball receiving top surface 17 of the 15 bottom is inclined slightly downwardly from the base edge 16 to the apex 15 so that the spheres or balls B hereinafter described will tend to roll down the incline towards the apex 15 after the balls have been shaken to mix the same, as 20 hereinafter described. The upper portion of the container comprises primarily a one-piece shell 18 which includes a flat upstanding base side 19 and two upstanding side walls 20 and 21 rounding into each other to form slightly curved dome 25 roof 22 considered transversely, that is, in planes parallel to the base side 19 as shown in Fig. 2. Considered from front to rear, that is, perpendicularly to the base side 19, the roof 22 converges, from its maximum height, at the crotch 30 23 formed by the juncture of the side walls 20 and 21 above the apex 15 as shown in Fig. 4. The roof is provided at its high forward point with an upstanding funnel 24 provided with throat 25 of sufficient diameter to permit the insertion, one by one, of the balls B.

The base side 19 is provided adjacent its opposite edges with two openings 26 and 27 of a size to permit the free passage therethrough of one of the balls but not of sufficient dimension 40 to permit two of the balls to pass therethrough out of the container at the same time. The openings have their lower edge flush with the high edge of the bottom 14 so that the ejected spheres when ejected from the container will 45 drop a short distance in falling on to the support 10 as shown in dotted lines in Fig. 4. The openings 26 and 27 are provided respectively with drop closures 28 and 29 normally held by virtue of their own weight or by their inertia in position closing their respective openings.

The closures 28 and 29 are secured to the wall 19 by hinges 30 located above the respective closures so that each closure while normally hanging vertically is capable of swinging out- 55

wardly when unlocked and thus form a drop door. The doors are each designed to be temporarily locked in closed position by means of a hasp 31 hinged to the lower edge of the closure 5 and designed to be secured by locking means 32 movable into inoperative or unlocked position by means of a spring pressed thumb piece 33. These thumb pieces are preferably designed to face inwardly that is, towards each other, as 10 shown in Fig. 2, and thus disposed in position to be conveniently moved outwardly relative to each other and into unlocking position by the thumb of the two hands of the operator as he grasps the opposite sides 20 and 21 at the corners adjacent 15 the base side 19. The crotch edge 23 is provided intermediate its height with an outwardly projecting horizontally disposed cylinder 34 provided with a bore 35 extending axially and horizontally therethrough. Slidably mounted in the 20 bore 35 is a bolt-like plunger 36, the inner end of which is formed with a cue head 37 simulating the head of cues such as the head of the cue 13. The outer end of the plunger 36 is threaded as indicated at 38 and is in threaded engagement 25 with an external head 39 preferably formed by mutilating a billiard ball to provide an internal bore 40 slidably mounted on the cylinder 34 to provide a horizontally extending bearing engagement between the head 39 and the projecting 30 cylinder 34. It is a feature of this disclosure that the outer exposed surface of the head 39 provides a spherical contact face 41 and otherwise the structure is designed so that the plunger head will simulate a billiard or pool ball for cooperative play with the free cue ball 12. The bore 40 forms a spring chamber containing a coiled spring 42 bearing at one end against the outer end of the cylinder 34 and at its other end against the 35 head 39 tending to urge the plunger outwardly. 40 A long narrow box-like partition 43 is located in the container between the openings 26 and 27 and projecting from the base side 19 a distance at least equal to the diameter of one of the balls and disposed so as to provide a pair of constricted passageways 44 and 45 leading from 45 the interior of the container to the openings 26 and 27. The partition is provided with a top 46 sloping downwardly from the base side 19 and underlapping the throat 25 and thus disposed 50 in position to receive the balls introduced into the throat and direct them off the top 46 and into the interior of the container to join the balls already there. 55 Within the container are twelve billiard balls 60 B each provided with a single number and forming two sets of numbered balls, each set being numbered progressively from 1 to 6 inclusive. The bottom 14 is so proportioned relative to the twelve balls when in position engaging the top 65 surface 17 of the bottom that they assume the pyramidal form illustrated in Fig. 3 with an apex ball marked "3" in this case centered in axial alignment with the direction of thrust of the plunger. The balls when falling into position 70 tend to arrange themselves in two lines in the form of a V with five balls in each line and with the apex ball common to both lines. The other three balls, as for instance those marked "6", "3" and "1", in the illustrated arrangement, are 75 located between the two lines of balls in the crotch of the V formed thereby. The inclined slope of the bottom 17 tends to shift the balls as a whole towards the right of the showing in Figs. 3 and 4 and thus away from the partition 43 and from the base side 16 provided with the

openings. While it is the intent to make the structure as small as possible and thus provide a container which can be readily lifted from its support in the shaking of the balls incidental to the mixing operation herein featured, sufficient 5 clearance 47 is provided so as to ensure the requisite freedom of movement between the several balls during the mixing operation. With the idea of making the structure as light in weight as possible it is suggested that the shell be made of sheet aluminum and the base made 10 of wood. 15

In operation and assuming that the balls are, for instance, in the position in the container as indicated in Fig. 3 and that the container is 20 centered at one end of the pool table as suggested in Fig. 1, the player strikes the cue ball 12 with cue 13 and aims for the head 39 either with a direct shot or with a bank shot in accordance with certain rules forming no part of the present disclosure. The objective insofar as this disclosure is concerned is to strike the spherical head 39 with sufficient force to overcome the reset spring 42 and cause the cue-like end of the plunger to strike a percussion blow against the 25 apex ball in this case shown to be one of the numbered "3" balls. This will cause both lines of balls "4", "2", "5", "1", at the upper side of Fig. 3 and balls numbered "4", "6", "5", "2", at the lower side of this figure to move slightly from 30 right to left in the direction of the lines. Assuming that the closures are unlocked, the impulse transmitted along the two lines of balls will cause the end ball and which in the instant illustration both happen to be numbered "4" to 35 leave the balance of the balls in the line and move rapidly and forcefully out of the two openings. This outward movement of the end balls elevates the closures as they pass beneath the same as indicated in dotted lines at the left of 40 Fig. 4. The two balls will then roll out of the container and on to the billiard table where they can be quickly read and utilized as part of the complete game. While the remaining balls of the line such as the "2", "5", "1", will not move very 45 far from their initial position, and this is especially true in those cases where the balls must move up the incline formed by the bottom, anyhow, the next succeeding balls "2" and "6" will not be moving under any material force. However, even though this next succeeding ball of each line be moving, it would not have sufficient force to elevate for the second time the dropped closure and in this way the dropped closure acts 50 selectively to permit while restraining the freedom of escape of the first ball in each line, and in preventing the second ball from moving outwardly it maintains all of the remaining balls in the container. In this way only two balls can be ejected from the container at one actuation of 55 the plunger and only then in the event that all twelve balls are within the container when the plunger is snapped. 60

After a play has been made the two ejected balls are replaced in the container through the 65 open top funnel and permitted to rejoin their companions remaining in the container. The fastening means at 33 are snapped into closed position, the container is elevated from its support and vigorously shaken in order to mix the 70 balls indiscriminately so that it will be a matter of chance as to what particular numbered balls will eventually occupy the most advanced position in each line and which in Fig. 3 are occupied by the two balls numbered "4". The container 75

with the mixed grouping of the balls is replaced on the table, the closures are unlatched and the device is ready for a repetition of the ball ejecting operation previously described.

5 It is obviously within the scope of the disclosure to operate the plunger by direct manual operation or by chance instrumentalities or by skill controlled instrumentalities other than the cue and cue ball aspect herein featured.

10 I claim:

1. In a device of the class described, the combination of a support providing a flat pool-table-like surface, a container of substantially triangular form in plan having two openings in its base side, each opening provided with a drop closure hingedly mounted above its respective opening, twelve billiard balls constituting two sets numbered one to six, said balls located in a single plane in the container with nine of the balls arranged 15 in the form a V, one line of the balls being in alignment with one of the openings and the other line being in alignment with the other opening, a plunger mounted at the angle of the container opposite the base side and adapted at its inner 20 end to contact with the ball forming the crotch of the V, the outer end of the plunger exteriorly of the container provided with a spherical ex- 25 posed contact face simulating a billiard ball, a reset spring acting on the plunger and tending 30 to project the spherical face outwardly away from the container, a free cue ball on the support exteriorly of the container and adapted to be moved forcefully, as by percussion from a cue in playing pool, into contact with the spherical face to move 35 the plunger inwardly against the resistance of its reset spring and thus cause the plunger to react along the two lines of balls to cause an end ball of each line to move out of the container 40 through the adjacent opening and against the resistance offered by the drop closure of such opening.

2. In a device of the class described, the combination of a mixing container for spheres, said container provided with a sloping bottom of triangular form in plan and with an end wall and two side walls coacting to group the spheres in the form of a triangular with an apex forming sphere at the lowermost point of the bottom when the spheres fall on the bottom at the termination of 45 a mixing operation, the end wall being at the wide side of the pyramid and provided with two openings therein adjacent the side walls and a plunger at the apex opposite the end wall, said plunger operable from the exterior of the container and 50 in engaging the sphere at the apex acting to eject from the container the two spheres which happen to be nearest the openings.

3. In a device of the class described, the combination of a container having a bottom triangular in plan and sloping downwardly from one base edge to an apex, an end wall and two upstanding side walls, the end wall opposite the apex provided with two openings adjacent the two side walls, drop closures for each of said openings hinged to said end wall, means for locking said closures at will, more than two numbered spheres 55 on said bottom disposed in two lines with a sphere common to both lines at the apex and with the spheres aligned with the openings and a percussion plunger mounted in the container at the apex and adapted in engaging said common sphere to eject the two spheres at the opposite ends of the lines out of the container through the 60 openings and against the resistance interposed 65

by the inertia of the closures when hanging in unlocked position.

4. In a device of the class described, the combination of a container having capacity to contain more than two billiard balls with sufficient clearance to permit the balls to be mixed by shaking the container with the balls therein, the bottom of the container being of triangular form to cause the balls automatically to assume a triangle form when they fall to the bottom, one of the upstanding walls of the container provided with two openings each of a size to permit only one billiard ball to pass therethrough at a time, and a plunger carried by the container opposite the wall having the openings and adapted in striking the ball at 15 the apex of the triangle to eject the two balls which happen to be nearest the openings therethrough and thus out of the container.

5. A container for billiard balls having an interior of sufficient capacity to permit the mixing 20 of the balls when the container is shaken violently, said container provided on one side thereof with a pair of openings, means for causing some of the contained balls to assume two lines of mutually contacting balls arranged in the form 25 of a V, and means acting on the ball at the apex of the V to eject the two balls at the opposite end of lines out of the container through the pair of openings.

6. A container for billiard balls having an interior of sufficient capacity to permit the mixing 30 of the balls when the container is shaken violently, said container provided on one side thereof with a pair of openings, means for causing a certain number of the contained balls to assume 35 two lines of mutually contacting balls arranged in the form of a V, said means including a bottom of triangular form sloping towards one apex for causing the balls to roll towards said apex and to position one of the balls at said apex, and means 40 acting on the ball at the apex of the V to eject the two balls at the opposite end of lines out of the container through the pair of openings.

7. In a device of the class described, the combination of a support, a ball-mixing container 45 for a group of numbered balls fixed to the support, means acting on the balls for arranging them in line and in contacting relation, said container provided with an opening at one end of the line of balls for discharging the same on to the 50 support, and ejecting means slidably mounted in the container at the other end for engaging the adjacent ball of the line.

8. In a device of the class described, the combination of a ball-mixing container for a group 55 of numbered balls, means acting on the balls for arranging them in line and in contacting relation, said container provided with an opening at one end of the line of balls and a plunger carried by the container at the other end for engaging 60 the adjacent ball of the line, and a bottom to the container inclined downwardly from the opening towards the ejecting means whereby the balls in rolling down the incline will contact with each other successively in line, with the ball at the 65 lower end thus automatically located in position to be engaged by the ejecting means.

9. A container for two sets of billiard balls and having capacity to permit the balls to be mixed when the container is bodily shaken, means for 70 causing the mixed balls to arrange themselves in two lines, said container provided with two openings, one for each of said two lines of balls and manually actuated means acting directly on that one of the contained balls which happens to be 75

nearest thereto to move the same to cause the balls forming the two lines to shift slightly towards their respective openings and thus act to eject from the container selectively only the two balls which happen to be nearest the two openings.

10. A container for two sets of billiard balls and having capacity to permit the balls to be mixed when the container is bodily shaken, said 10 container provided with two openings and means acting directly on the contained balls to eject from the container only the two balls which happen to be nearest the two openings, and closures

for the openings and constituting gravity controlled means tending to defeat the ejection from the container of any of the balls except such two balls.

11. In a game device, the combination of means forming an enclosure, a plurality of sets of similarly numbered balls in the enclosure, means for automatically arranging two of said balls in the enclosure in position to be ejected from the enclosure and a single plunger operatively disposed to eject said two balls simultaneously from the enclosure. 5 10

JOHN H. GROSS.
